UNITED STATES PATENT OFFICE.

ZENAS H. BROWN, OF CLEVELAND, OHIO.

BURNER FOR NATURAL GAS.

1,253,781.

Specification of Letters Patent. Patented Jan. 15, 1918.

Application filed February 24, 1917. Serial No. 150,789.

To all whom it may concern:

Be it known that I, ZENAS H. BROWN, a citizen of the United States, residing at Cleveland, in the county of Cuyahoga and State of Ohio, have invented certain new and useful Improvements in Burners for Natural Gas, of which the following is a specification, reference being had to the accompanying drawings.

10 This invention relates to gas burners and particularly to gas burners designed for heating.

One of the objects of my invention is to produce a flame for heating purposes which 15 will be, to a certain extent, like the green flame produced by a Bunsen burner, but without the attending blue flame and in which the green heating flame may be distributed over a relatively large surface so 20 as to distribute the heat.

By long and careful experiment, and after the trying out of many forms of burners designed to achieve the purpose above related, I have devised the construction 25 which is illustrated in the drawings hereto. By my first experiments, I produced the green flame of the Bunsen burner, but this green flame, when produced, was as incapable of proper control as in the Bunsen 30 burner itself and would blow out when supplied with too much air or too much gas. Eventually I produced a burner that would hold the green flame, no matter how much air or gas was taken into it, but the heat was 35 too concentrated and not enough diffused, and the burner was very noisy, these objections rendering it of no value for the purpose for which it was intended.

In the course of my experiments, I discovered that too great or excessive pressure 40 was what caused the Bunsen flame to blow out and I discovered that only by the proper equalization of pressure in the burner, would the green flame be controlled and utilized 45 for the purpose intended. After further experiments I produced the burner which forms the subject matter of this application and in this burner the flame is about the same shape as that given off by the "Rochester" lamps and is as easily controlled. By 50 my invention I have provided a burner of this character in which the flame can be raised and lowered very easily and delicately and in which the flame may be turned down to $\frac{1}{2}$ of an inch, with no danger of blowing out, or in which the flame can be

raised to a height of two inches and still retain its intense green color and its very great heating properties. Furthermore, by the mechanism which I will now describe, 60 I have provided a burner in which the flame is entirely silent and is absolutely odorless and one in which a minimum of gas is consumed with a maximum amount of heat, and furthermore I have provided a burner 65 wherein natural gas may be used, the burner being particularly designed for the burning of natural gas.

With the above named objects in view, I have constructed the burner which is illustrated in the accompanying drawings, 70 wherein:

Figure 1 is a vertical sectional view through a burner constructed in accordance with my invention; 75

Fig. 2 is a section on the line 2—2 of Fig. 1;

Fig. 3 is a vertical sectional view of the valve controlling the discharge of gas;

Fig. 4 is a face view thereof;

Fig. 5 is a fragmentary sectional view of the burner, with the angle of wall 13 exaggerated.

These figures are approximately three-quarters of full size. 85

Referring to these drawings, it will be seen that the burner comprises an air and gas intake tube designated 10, which, as illustrated is horizontal and may be supported in any suitable manner and which is 90 provided at one end with the upwardly turned pipe section 11. The interior diameter of the pipe section 11 and of the tube or pipe 10 is approximately the same for the entire length of the intake tube and 95 pipe section.

Supported upon the pipe section 10, in any suitable manner, as for instance by the collar 12, is the outer casing or jacket of the burner, designated 13. This is approximately cup shaped, that is, it has an annular bottom through the center of which the pipe 11 extends and has an annular side wall which extends upwardly and slightly outward and at its upper end is outwardly 105 deflected to form a rim 14. The pipe 11 extends upward nearly to the upper end of the casing 13 and disposed above the pipe 11 is a plate or disk 15, whose diameter is the same as the exterior diameter of the deflected portion 14 of the casing 13. From 110 this plate extends downward an annular

wall 16, formed at its lower end with a plurality of feet 17, which rests upon the bottom of the casing 13 and also formed preferably with a plurality of perforations 18 adjacent the lower end of the wall. Preferably this wall tapers downward from the plate 15 for the purpose which will be later stated.

It will be seen now that surrounding the upper portion of the pipe 11 is a chamber 19, which expands in area downwardly and that surrounding the wall 16 is a chamber 20, whose cross sectional area expands upward very slightly and that this chamber 15 suddenly expands at its upper end into the space 21 and that leading from this space 21 is an annular opening 22, from which the gas flame issues between the upper edge of the casing 14 and the perimeter of the plate 15. The plate 15 may be centered by any suitable means, as for instance, by the set screws 23 and the plate may also be vertically adjusted by these set screws, if desirable. These set screws are preferably provided with lock nuts 24, whereby the set screws are held locked and the parts held from any accidental displacement.

The outer end of the tube 10 or intake pipe is formed with an annular flange 25 forming an intake mouth and opening to the outer air. Preferably also, the tube 10, adjacent its intake mouth, is provided with a plurality of air inlet openings 26 disposed at uniform intervals.

35 Mounted in any suitable manner opposite the mouth of the intake pipe 10, is a valve fitting or casing 27, which is connected in any suitable manner to a gas pipe 28 leading from a source of supply. In the fitting 27 there is provided an ordinary valve 29, which, when closed, entirely cuts off the supply of gas passing through the fitting 27. The end of the fitting 27 is directed toward the axial center of the intake pipe 10 and is provided with a peculiar form of valve, which is of great importance in my device. This valve is illustrated in detail in Fig. 3. The extremity of the fitting 27 is formed with an exteriorly screw threaded nipple 30 and mounted upon the end of this nipple is a conical pin 31. The end of the nipple at intervals around the conical pin is formed with outward openings 32. Mounted on the screw threaded nipple is a sleeve 33 having a concave convex cap 34 formed with a central aperture 35, this aperture being slightly larger than the base of the conical pin 31, so that even when this cap is adjusted so that the wall of the aperture 35 surrounds the base of the conical pin 31, a slight annular space will be left between the wall of the aperture 35 and the conical pin 31. The sleeve 33 and the cap 34 may be shifted outward on the nipple, so as to thereby shift the cap longitudinally of the conical pin 31 and

to this end I attach to the rear end of the sleeve 33, a disk 36 having a radially projecting handle 37. Disposed in conjunction with the disk 36 and the handle 37 is a stop pin 38 which permits, ordinarily, nearly one entire revolution to be made by the sleeve 33, the disk 36 and the handle 37. When the handle 37 is turned in one direction and is stopped by the pin, the gas is almost entirely shut off. When it is turned in the other direction, however, and stopped by the pin, a maximum amount of gas for ordinary purposes is permitted to be ejected from the openings 32 and the opening 35. By removing the stop pin and rotating the valve in one direction or the other, however, a larger or smaller amount of gas may be provided for and at the same time provision may be made for using a minimum amount of gas or a maximum amount of gas, within the limits of the adjustment. The valve which is formed by the parts 31, 33 and 34 is usually adjusted to consume about 5 cubic feet of gas per hour, when the lever arm 37 is turned in one position and when the arm 37 is turned in the opposite direction and engaged with the stop screw 38, then the burner will consume up to about 15 cubic feet of gas per hour, which is the point of its greatest efficiency. It will be obvious, however, that the burner may be adjusted at any place between the two points to suit the ends of the operator. It will be likewise seen that there is a relatively very great amount of air consumed in comparison with the gas consumed and it is for this reason that I secure the green flame, which is so particularly desirable.

I have illustrated my device as being used in connection with a furnace having a crown plate 39 against which the flame from the burner is directed and have also shown a furnace having an outside jacket 40 and an inside jacket 41 defining a hot air space between them with which the openings 23 communicate so that as a current of air constantly passes through the chamber defined by the walls 40 and 41, this air will be taken into the intake pipe through the openings 26. The object of providing the openings 26 in the intake pipe is that a plurality of jets of air, as they may be termed, will enter the intake pipe at right angles to the main body of air entering the intake pipe and that thus a much better mixture will be produced than would otherwise be the case. Preferably there are only three of these openings 26, one at the bottom of the tube 10 and two on the sides.

One of the very important features of this burner resides in the particular construction of the casing 13 and the form of the chambers 19, 20 and 21. The object of the form and arrangement of the chambers 19, 20 and 21 is to regulate or control the pressure and

to allow the gas mixture to have proper expansion. The chamber 19, as before stated, expands in cross sectional area downward so that the mixed air and gas expands as it moves downward through this chamber and thus the gas does not rush into the next chamber 20 with too great a velocity. The chamber 20 has a nearly uniform area from its lower end nearly to its upper end and then expands suddenly into the space 21 and thus the fuel is allowed a sudden and final expansion before arriving at the point of combustion. The plate 15 is formed so as to have exactly the same diameter as the outside diameter of the casing 14 and the interior face of the outer wall of the chamber 21 should be machined out very carefully, as any unevenness on the inner face of the outer wall of the space 21 and unevenness of the walls of the chambers 19 and 20 is liable to cause the flame to burn unevenly.

The flame produced at the opening 22 is about the same in shape as the flame on the Rochester lamp burner and it can be raised or lowered by adjustment of the handle 37 of the valve. As it takes the proper amount of air at the intake pipe inlet, there need be no adjustment of the air, and the flame at the opening 22 may be turned down to a height of $\frac{1}{2}$ of an inch with no danger of blowing out, or the flame may be raised to a height of nearly two inches and still retain its intense green color and its intense heating power. The flame, while being perfectly silent, is absolutely odorless and the products of combustion from this flame may be even carried directly into the living rooms of the house, with no deleterious effect. Each burner of the character described, at its maximum flame height for the size illustrated will consume only 15 feet of gas per hour and with proper radiation 5 of these burners will be sufficient to heat an ordinary sized 8 room house, in the coldest weather. This has been demonstrated by actual tests and experiments. One burner has a capacity for heating a room 20 feet square in cold winter weather with a minimum consumption of gas and it will be obvious that this is a great saving of gas compared with the amount of gas consumed in ordinary heating burners.

It is to be noted that if the gas valve were allowed to be fully open, which is impossible with the construction which I have devised, then the air supply would not be adequate to produce a green flame and the burner, instead of being absolutely odorless, as it now is, would not only produce fumes, which would be deleterious to health, but the efficiency in heat units would be decreased with a larger consumption of gas. The crown plate 39, in whatever form it may take, plays an important part, as it acts as a spreader for the flame and when properly installed

beneath the crown plate, or equivalent device, the flame will burn as steadily and quietly as the flame on an ordinary lamp.

Attention is again called to the fact that the chamber 19 expands in cross sectional area downward, while the chamber 20 expands in cross sectional area upward. The increasing of the cross sectional area downward in chamber 19 would be of little or no use, unless the chamber 20 was also increased in cross sectional area upward. This increase is very slight from the bottom to the top of the chamber 20, but it is sufficient to prevent too great pressure at the point of discharge, as it is greatly assisted by the sudden increase in cross sectional area of the chamber 21. This chamber 21 is one of the most important features of the burner, as the gaseous mixture is allowed a sudden expansion in this chamber and is not forced into the opening 22 with such great force as to cause the flame to be lifted from the burner.

While I have illustrated the particular form of valve which is important in that it insures perfect results and prevents a person accidentally turning out the gas or turning up the gas too high in proportion to the amount of air to be used, yet I do not wish to be limited to this form of valve as other forms might be used having the same general effect. Neither do I wish to be limited to the details of construction which I have illustrated, as these details might be modified, in many ways, without departing from the spirit of the invention and it will also be obvious that the relative size of the device might be changed depending upon the work to be done and the heat to be secured, but I have found the proportions illustrated should be kept to quite closely. If the burner was made much larger in proportion, the normal gas pressure would not be enough to operate it properly, as the gas would not carry enough air into the burner to produce the full green flame on the upper portion of the flame, that is, about one-half of it would be blue.

If the burner were made much smaller than the proportions shown, there would not be enough space within the chambers to retain enough of the gaseous mixture to be heated before arriving at the point of combustion and further in order to secure a proper operation of the burner, there should be sufficient force in the gas issuing from the nozzle 30 to produce a jet and if the flow of gas is cut down to almost nothing, it will not draw enough air into the pipe 10, even though the pipe 10 be made of a smaller size in proportion to the jet. It requires quite a little force of gas entering the pipe 10 to produce the green flame.

The use of the chamber 19 does not make so much difference, as this chamber practi-

cally forms merely a container to hold the gaseous mixture while it is being heated by contact with the side walls of the chamber. It is, however, necessary in order to secure 5 the best results and to act as a mixing chamber for the air and gas.

A green flame would be produced even if only the air intake pipe were used, together with a needle valve, and if the casing 13 10 and casing 16 and plate 15 were removed, but on account of the excessive amount of air, the flame would immediately blow out and if the air supply were cut down sufficiently to hold the flame on the top of the 15 burner, the flame would have the form of two cones, a green flame cone and a blue flame cone. Furthermore, the flame would sputter and roar and unburnt gas would be thrown from the flame. If the air supply 20 were cut down still further, a blue flame would be formed which, while it would not make any noise to speak of, would give only a relatively small heat. I do not wish to be limited to the particular form of needle 25 valve which I have illustrated, as other forms of controlling valve might be used, but the valve is designed as a protection against the accidental turning off of the gas, as the valve is not quite closed when turned 30 to its lowest point and without the stop 38 the operator could very easily close it entirely without knowing it, as the action is very delicate. The plate 36 with the handle 37 constitutes the means for operating the 35 valve and this plate 36 might be provided with graduations indicated in dotted lines at 34 and coating with the index member 36^a (see Fig. 1) whereby the number of 40 cubic feet of gas that the burner is consuming per hour can be very readily indicated. It is essential that the outlet of the needle valve or nozzle 30 shall be disposed approximately $\frac{1}{2}$ " or 1" from the mouth of the air intake pipe as thereby the correct 45 amount of air is furnished to the pipe 10. The nozzle could be projected into the pipe 10, but the result would not be as good. A spider, connecting the nozzle or the needle valve and the open end of the intake pipe, 50 might be used if the spider were so constructed as to cause no interference with the air.

I have illustrated an annular slit 22 as the exit opening by which the mixed air 55 and gas issues from the casing 13. I do not wish to be limited to the exact form of this exit opening, but have found it to be extremely efficient in practice. A series of small holes might be used in place of the 60 slit 22 but while this would make no difference with the production of the green flame, yet the flame would jump from the burner as the blank space between the perforations would create a pressure at the outlet 65 perforations and this would destroy the equaliz-

ing action of the chambers 19 and 20 unless the holes were made large enough so that they would furnish no greater resistance than the annular passage.

It will be noted from Fig. 1 that the outward divergence of the wall 13 with relation to the partition wall 16 is very slight but without this slight increase, I have found by actual tests that the fuel will be delivered too forcibly to the flame even 70 though the fuel be delivered into the chamber 21. I find, however, that this slight increase is absolutely necessary in order to make the flame burn properly and to maintain a perfect balance in the burner. The 75 fact that this chamber 21 holds a relatively large amount of fuel in readiness at the point of combustion, would seem to steady the flame and seems to furnish a more even supply of fuel than it would 80 without it. The chamber 19 does not have any particular effect in securing a gradual expansion of the fuel but it is necessary to serve as a container whereby a sufficient quantity of the fuel may be properly heated 85 before it is delivered to the flame. Of course, the heating process begins to take place as soon as the fuel enters that portion of the pipe 11 disposed within the burner and continues all the way through 90 the burner and the contents of chamber 20 and its enlargement 21 will naturally be hotter than the contents of chamber 19. The perimeter of the plate 15 and the deflected portion 14 are the hottest points on the 95 burner. The partition 16 is, of course, necessary, as, if it were not there, there would be no gradual release of the fuel and the pipe would deliver immediately into the upper end of chamber 20 and the entire effect of 100 the burner would be spoiled.

Having described my invention, what I claim is:

1. In a burner of the character described, a relatively large air intake pipe, means for 110 discharging air and gas into the inlet end of the pipe, a casing surrounding the outlet end of the pipe and having a top disposed in slightly spaced relation to the extremity of the intake pipe, the outer wall of 115 said casing at its end adjacent said top being formed with a sudden annular enlargement, and the end of said enlarged portion of the wall being spaced from the top to form an annular opening through which the 120 ignited gas may issue, the top having a diameter the same as the outer diameter of the casing and having an annular partition surrounding the intake pipe, but spaced therefrom and from the exterior wall and 125 having openings between the partition and the bottom of the casing for the passage of gas.

2. In a burner of the character described, a relatively large air intake pipe, means for 130

discharging air and gas into the inlet end of the pipe, a casing surrounding the outlet end of the pipe and having a top disposed in slightly spaced relation to the extremity 5 of the intake pipe, the outer wall of said casing at its end adjacent said top being formed with a sudden annular enlargement and the end of said enlarged portion of the wall being spaced from the top to form an 10 annular opening through which the ignited gas may issue, the top having an annular partition surrounding the intake pipe but spaced therefrom and from the exterior wall and having openings between the partition 15 and the bottom of the casing for the passage of gas, said partition defining a chamber between the intake pipe and the partition, which chamber expands cross sectionally from the top of the casing toward the 20 bottom of the casing, said partition defining between it and the surrounding wall an annular passage having an upwardly increasing diameter and opening into said first named enlargement of the casing.

25 3. In a burner of the character described, a relatively large intake pipe, means for directing air and a jet of gas into the inlet end of the pipe, an annular casing surrounding the outlet end of the intake pipe, said 30 annular casing having a diameter about twice the diameter of the inlet pipe and a depth approximately the same as its diameter; and having a bottom and an outer wall, the outer wall at its upper end being laterally offset to thereby form an annular 35 enlargement, a top having a diameter equal to the exterior diameter of the outer wall

at its upper end and having an annular partition depending from the top and a seating on the bottom of the casing, the top 40 being spaced from the edge of the wall of the casing to form an annular flame opening, and means for centering the top and annular wall.

4. A burner of the character described including a relatively large inlet pipe having a practically uniform diameter from end to end, a casing surrounding one end of the pipe, the opposite end of the pipe being entirely open for the inlet of air and being 45 provided adjacent this open extremity with orifices in its wall through which additional air may pass, a gas discharge nozzle spaced from the open end of the pipe but directed toward said open end, means for controlling 50 the amount of gas issuing through said nozzle, said casing having a diameter approximately twice that of the pipe, and having an upwardly and outwardly inclined wall, the wall at its upper end being outwardly 55 extended and then upwardly extended to form an annular enlargement, a top plate disposed in slightly spaced relation from the upper end of the casing and having a diameter equal to the diameter of the casing at its upper end, said top plate carrying a baffle wall extending downward nearly to the bottom of the casing.

In testimony whereof I hereunto affix my signature in the presence of two witnesses. 70
